UNITED STATES PATENT OFFICE.

ERNST FRISCHMUTH, OF SIEMENSSTADT, NEAR BERLIN, GERMANY.

KEY FOR COMBINATION LOCKS.

Original application filed May 4, 1923, Serial No. 636,605. Divided and this application filed December 10, 1924. Serial No. 755,087.

My invention relates to improvements in keys for combination locks. This type of locks is locked by pins passing from the stationary part of the lock into the rotatable part. These pins are transversely divided and are adapted to be longitudinally displaced by the key against the resistance of springs in such a manner that their joints coincide with the joint between the parts of the lock. For that purpose the key is fitted with a number of pins of unequal length, but each pin of a definite length. If this would not be the case, the pins in the bores in the lock would be forced back too little or too much that not all the joints in the pins would coincide with the joint between the parts of the lock and the cylinder or the drum would not be turned. If, however, an unauthorized person had an opportunity to handle the key, he would be able to measure the length of the pins and to copy the key for his own use to open the lock in thievish intention.

The object of my invention is to provide a key which may be so adjusted by simply turning a nut that it becomes at once useless for opening the lock. The owner need therefore only turn the nut after using the key. An unauthorized person is then no longer able to open the lock with the key and a copy of it is equally useless.

An embodiment of my invention is illustrated in the drawing affixed to this specification and forming part thereof. In the drawing represents:

Fig. 1 a sectional elevation

Fig. 2 an elevation at right angles to Fig. 1

Fig. 3 a plan and

Fig. 4 a detail.

Similar parts are indicated by the same numerals of reference throughout all the figures of the drawing.

Referring to the Figs. 1, 2 and 3 it will be noted that the shaft 12 of the improved key is furnished at its front end with a short bit 13 and with a cylinder 14 provided with bores for the operating pins 15. Upon the rear portion of the shaft a micrometer screw thread 16 is provided and upon this screw is mounted the key ring 17, which is secured against rotation by a fixing pin 18. The operating pins of the key are at their lower ends provided with heads 19 and are forced by springs 20 against a cam or steel plate

of uneven surface 21. The cam plate 21 is housed in a short sleeve 22. Behind it a nut 23 rides upon the screw thread 16. The plate 21 and the sleeve are connected with the nut 23 by a pin 24, so that they are obliged to take part in its rotation. The cylinder 14 and the sleeve 22 are provided with divisions upon their circumference by means of which the correct position of the pins for operating the lock can be adjusted. In this correct position the nut 23 may be locked by a counter nut 28.

If it is desired to render the key useless for an unauthorized person, the nuts 24 and 23 are turned in one or the other direction. Owing to the uneven or cam surface of the plate 21 the pins 15 are then unequally adjusted so that the key can no longer be used for unlocking the lock.

If it is desired in such keys to interchange the locking pins 15 together with the control pins in the lock, the pins are preferably made of a special construction as the length of the pins must be changed with regard to the face cam 21. A pin which easily admits of such a change is shown in Fig. 4. It consists of a topped part 25 into which a screw 26 with a transverse hole through the head is screwed. By screwing the screw 26 more or less into the part 25 the length of the pin may be reduced or increased. In order to lock the screw 26 in the part 25 the latter may be split at the screw-threaded end. Preferably grooves 27 are cut into the part 25, which increase the difficulty in opening the lock by probing.

It will be understood that I do not limit myself to the exact details of construction shown in the drawing as these may obviously be modified in many ways without departing from the spirit of my invention or sacrificing any of its advantages.

What I claim as my invention is:

1. A key for a combination lock comprising in combination a shaft, a cylinder having bores being an integral part of said shaft, headed pins in said bores adapted to be moved longitudinally to projected or retracted position, springs in said cylinder bores tending to force the heads of said pins to retracted position and a rotatably movable cam plate for controlling the movement of said pins.

2. A key for a combination lock comprising in combination a shaft, a cylinder

with bores mounted on said shaft, headed pins in said bores, springs in said cylinder bores tending to force the heads of said pins rearwards, an abutment plate against which the heads of the pins are adapted to be forced by said springs and a nut connected with said plate riding upon a screw-threaded portion of the key shank adapted to move said plate and to adjust said operating pins and means for facilitating their exact adjustment.

3. A key for a combination lock comprising in combination a shaft, a cylinder with

bores mounted on said shaft, headed pins in said bores, springs in said cylinder tending to force the heads of said pins rearwards, a face cam against which the heads of the pins are adapted to be forced by said springs and a nut connected with said face cam riding upon a screw-threaded portion of the key shank adapted to move said face cam and to adjust said operating pins and means for facilitating their exact adjustment.

In testimony whereof I affix my signature.
ERNST FRISCHMUTH.
